WINDOWPANE AND METHOD OF MAKING
SAMEJames Bailey and Aaron K. Lyle, Hamburg, N. Y.,
assignors to Bailey & Sharp Co., Inc., Ham-
burg, N. Y.

Application March 2, 1936, Serial No. 66,540

15 Claims. (Cl. 20—56)

This invention relates to window constructions, and particularly to the reinforced glass panes therefor and the mounting of the same in a sash.

In the ordinary method of assembling panes of glass in a window, the sash is recessed to receive the glass. The pane is bottomed in this recess either directly against the sash or on a thin layer of putty or the like. The remainder of the recess is then filled with putty.

Under these conditions, the central area of the glass is exposed to any incident radiation whereas the edge portions are protected from such radiation by the shadow of the sash and putty. Glass, being a fair absorber of long wavelength radiation, is considerably heated by sunlight or by radiant heat from a furnace. It is also a poor conductor of heat. The mass of glass and putty, and the sash particularly if a steel sash is used, tends to prevent the edges from heating up as rapidly as does the central portion of glass. On some experiments we have found that the difference in temperature between the glass where it is directly exposed to the heat and the glass where it is protected by the sash and putty may at times amount to as much as 100° F.

Further, heat absorbing glasses heat up quite rapidly when exposed to the direct radiation of bright sunlight and in some cases the shadow of the sash alone is sufficient to cause a very material temperature difference.

Now, if the central portion of glass is hotter than the edge portion, the center will expand more than the edge. This results in compressive strains in the central portion and much greater, because of the smaller amount of material, tensile strains in the edge portion. The edge portion contains all of the cracks and splinters due to cutting and is therefore mechanically weak. It will consequently break quite easily.

We have found that panes of rolled wire glass are particularly weak in the edge portion due to the cracking, chipping and splintering of the glass when the wire is broken. Further, the pattern on the surface, especially if it is of a deep and prismatic design, seriously weakens the edge along the cut. As a result rolled wire glass is particularly likely to crack from radiant heat.

An object of this invention is to provide an improved reinforced glass pane for use in window constructions, with which breakage or cracking of the glass from radiant heat will be reduced, which may be incorporated in sash of existing constructions without changes in the construction of the sash or the manner in which the pane is secured in the sash, with which the

effective strength of the pane in a sash will not be materially weakened, with which the cost of the pane or of the window construction in which the pane is used will not be materially increased, and with which the appearance of the window construction will not be materially changed.

Another object of the invention is to provide an improved window construction of the type utilizing a reinforced glass pane, with which danger of breakage due to uneven expansion throughout the pane is reduced, with which the cost of construction is not materially increased, and which may be incorporated in relatively long panes.

Another object of the invention is to provide an improved method of making a window construction utilizing a reinforced glass pane, by the use of which, danger of cracking of the pane due to uneven heating of different zones of the pane will be materially reduced, and which will be relatively simple and easily practiced.

Various other objects and advantages will be apparent from the following description of some embodiments and examples of the invention, and the novel features will be particularly pointed out hereinafter in connection with the appended claims.

In the accompanying drawing:

Fig. 1 is a perspective of a portion of the sash having attached thereto a reinforced glass pane constructed in accordance with this invention and illustrating one embodiment thereof;

Fig. 2 is a plan of a corner of a reinforced glass pane, which may be secured in a sash of usual construction, constructed in accordance with this invention;

Fig. 3 is a sectional elevation of the same, on a larger scale, with the section taken approximately along the line 3—3 of Fig. 2;

Fig. 4 is a sectional elevation on a larger scale through a portion of a sash having mounted therein a glass pane also constructed in accordance with this invention and illustrating another embodiment or example thereof;

Fig. 5 is a plan, on a reduced scale, of a portion of a window construction of the type used in greenhouses and the like, and which is also constructed in accordance with this invention;

Fig. 6 is a plan, at approximately actual size, of a portion of one of the glass panes shown in Fig. 5; and

Fig. 7 is a sectional elevation, on a slightly enlarged scale, of a glass pane also constructed in accordance with this invention, and illustrating

the application of this invention to the type of pane commonly known as a shatterproof pane. In the embodiment of the invention illustrated in Figs. 1 to 3, a reinforced glass pane 10 constructed in accordance with this invention is mounted in the conventional manner in the recess or rabbet 11 of a sash 12. The sash 12 is shown as a standard steel sash, utilizing a strip of putty 13 to hold the pane in position in the rabbet or recess 11. In this type of glazing a thin layer 14 of the putty is disposed in the bottom of the rabbet 11 before the marginal edge of the sash is placed in the sash. The pane is placed against this layer and the recess filled with the remainder of the putty in the usual manner. In this embodiment of the invention, the reinforced glass pane is illustrated as of the type known as rolled wire glass, in which a woven wire screen 15 of large mesh is embedded in the glass and is co-extensive in area with the faces of the glass. This glass may have the reinforcement embedded only to a slight extent into the glass such as shown in Figs. 1 to 4, or it may be disposed approximately equidistant between the faces of the pane of glass, as usual in the window pane industry.

After the glass pane is cut to the desired size, the glass of a marginal strip thereof, which is to be secured to the sash or secured to any suitable support in which it may be covered or protected from heat radiation to any extent, is cut, broken or severed from the body of the pane along the line 16, without severance of the reinforcing wires of the screen 15. This severed marginal edge strip A is then disposed in the recess or rabbet 11 of the sash and glazed in the usual manner with the crack or line of severance 16 running in the direction of the recess or rabbet 11 and just within the rabbet, as shown in Fig. 1, so that the uncut marginal edge of the pane will be received somewhat in the rabbet or recess 11, as shown in Figs. 1 to 3. In many cases, the cut may be located about one-half inch in from the edge, at a place where the cut will be just covered by the edge of the putty. The putty or other similar plastic glazing material 13 is then brought over the crack or line of severance 16, as shown in Figs. 1 and 3, in order to cover and seal the crack or line of severance. The crack permits expansion and contraction of the central or body portion relatively to the anchored edges or strips A. While the strip A may be broken under the putty, by this expansion, the crack cannot extend into the exposed part or body portion.

The putty 13 prevents the entrance of moisture into the crack 16 such as would cause rust or deterioration of the wire reinforcement where it joins the marginal edge strip A to the main body of the pane. In some instances it may be desirable to stretch slightly the wires of the reinforcement at the cracks or lines of severance, immediately after the crack is formed, as shown particularly in Figs. 1 to 3, in which case the slightly widened crack will be covered and protected by the putty 13, yet the crack of substantial width allows limited expansion and contraction of the main body of the pane without material displacement or movement of the marginal section A. Preferably, such marginal, partially severed strips A of the pane are provided on all of the edges which are secured in the sash or to a support.

In the embodiment of the invention shown in Fig. 4, the crack along lines 16, particularly after

being enlarged or widened by the stretching of the wires of the reinforcement following cracking or severance of the glass along lines 16, is filled with a resilient, plastic material which preferably has the property of adhering to the glass, is transparent and weather resistant. Such filling materials are well known in the glass industry. For example, a cellulose base material is used in the formation of what is popularly known as shatterproof glass, and such material in plastic form may be used to fill the cracks provided in this manner. Other materials which may be used, although, in some instances, less transparent, are shellac, asphalt cellulose materials dissolved in vaporizable solvents, and organic resins containing a suitable plasticizer and of the type suitable as a plastic cement, and which may be poured or worked in a plastic stage.

Any of the organic resins which may be worked in a plastic stage and then hardened somewhat, such as by the vaporization of a solvent, may also be employed. Synthetic resins, including various condensation resins, and containing a plasticizer, which are capable of being worked in a plastic stage and subsequently hardened, are also suitable, but since such resinous materials are well known in the art, a detailed list is omitted. When the cracks along lines 16 are filled with this resilient, plastic material 17, Fig. 4, it is not necessary to place the cracks beneath the putty 13, although the filled cracks should be disposed either under the putty or in reasonably close proximity to the sash, if one is to obtain the maximum benefits of the invention.

In Fig. 5 the invention is illustrated as embodied in the roof of a greenhouse where the panes are overlapped in shingle fashion and secured only along opposite side edges. In this construction, the sash bars 18 extend for the whole width of the roof in the direction from eaves to ridge pole, and the panes 10 are disposed along their opposite side edges in the grooves or rabbets 11 of these sash members 18, with adjacent edges of the panes that lie between the same pair of sash bars or elements slightly overlapping, shingle fashion, as at 19. The two opposite side edges of each pane which are received in the sash bars are provided with the cuts or cracks 16 creating the side strips A in the manner shown in Figs. 1 to 3. These cracks 16, if unfilled, are protected by the putty, as shown in Figs. 1 to 3, but if filled with the resilient plastic material 17, they need not be, but may be, covered by the putty.

Where very long panes of glass are employed, as shown in Fig. 5, the relative expansion between the central portion and the parts or strips A covered by the putty may be sufficient to overstrain the reinforcement wires, and this we may prevent by providing a plurality of transverse cuts or cracks 20 similar to cracks 16 extending from the cracks 16 across the strips A to the adjacent edges of the pane. These transverse cuts 20 may be arranged every few inches, and they provide a multiplicity of expansion joints which limit the movement at each joint. If a seal is employed where the panes overlap as at 19, the lower or covered edge at each overlap should preferably be protected from possible breakage by a crack or cut 16 along that edge, somewhat beneath the overlap if open or unfilled, or adjacent the overlap if filled with the resilient plastic material 17. This effectively prevents possible breakage along the overlapping edges of the panes.

In Fig. 6, the positions of the cuts 20 and 16 are illustrated on a somewhat larger scale than in Fig. 5.

In Fig. 7, the invention is illustrated as applied to glass of the type known as shatter-proof glass, in which sheets 21 and 22 of glass are secured by suitable cement layers 23 to the opposite faces of a sheet 24 of celluloid or similar cellulose material. Glass made in this manner is well known in the art and in common use in the windows and windshields of motor vehicles. When using this type of glass pane in which the celluloid interposed sheet is the reinforcement, the glass is cut along the marginal edges as at 25 in both sheets 21 and 22, that is both sheets 21 and 22 are cut or severed down to the interposed celluloid sheet, and this celluloid sheet or central layer then anchors the severed glass portions B to the body portion in the same manner that the wire reinforcement in Figs. 1 to 6 unite the severed marginal glass strips A to the body of the pane. The cracks 25 may also be filled with a resilient plastic material 26 which is similar to the material 17 in Fig. 4. Panes formed in this manner are used in the same manner as those described for Figs. 1 to 6, and the marginal strips B may be subdivided by transverse cuts similar to the cuts 20 of Figs. 5 and 6 wherever relatively long panes are employed.

While we have found it advisable, in most cases, to locate the cracks or cuts 16 and 25, so that they are just covered by the putty in the sash grooves, it will be understood that considerable latitude is possible in the location of such cuts or cracks within the broader aspects of the invention. If the cut or crack is located about half way back in under the putty, then only about two-thirds of the possible benefit is ordinarily derived. Obviously very severe conditions such as the use of heat absorbing glass in large panes in the Tropics will require the use of a putty 13 which contains a certain measure of plasticity.

The use of the cuts 16 and 20 in rolled wire glass in accordance with this invention has made panes of such glass with these cuts substantially immune to breakage from radiant heat, even under severe conditions.

It will be understood that various changes in the details, materials and steps which have been herein described and illustrated in order to explain the nature of the invention, may be made by those skilled in the art within the principle and scope of the invention, as expressed in the appended claims.

We claim as our invention:

1. A window construction comprising a glass pane having reinforcement contained therein, a sash recessed to receive the glass, putty filling the recess to seal the joint between the glass and the sash, the entire marginal edge portion of the glass within the recess of the sash being severed from the central portion of the glass beneath the putty and with the reinforcement unsevered.

2. In a window construction of the type having a recessed sash and an edge portion of the glass pane secured in said recess, and with a body of putty filling the recess and concealing the joint between the glass and the sash, that improvement which comprises a pane of rolled wire glass having an edge portion disposed in said recess and covered by said putty, said glass having a marginal strip of said edge portion within the recess severed from the central portion of the glass pane without severance of the reinforcement.

ing wires, and with the line of severance within the recess and concealed by the putty.

3. In a window construction of the type having a recessed sash and an edge portion of the glass pane secured in said recess, and with a body of putty filling the recess and concealing the joint between the glass and the sash, that improvement which comprises a pane of rolled wire glass having an edge portion disposed in said recess and covered by said putty, said glass having a marginal strip of said edge portion within the recess severed from the central portion of the glass pane without severance of the reinforcing wires, the line of severance being just slightly within the recess and concealed by the putty.

4. In a window construction, a sash having a recess, a pane of rolled wire glass having an edge portion received in said recess, the glass of said marginal edge portion within the recess being severed along a line parallel to the recess and just within the recess, without severance of the reinforcing wires, and putty-like means for filling the recess and covering the line of severance in the glass of said pane.

5. In a window construction, a sash having a recess to receive a marginal edge of a glass pane, a pane of rolled wire glass having a marginal edge disposed in said recess, the glass of said pane along said marginal edge and within said recess being severed from the body portion of the pane without severance of the reinforcing wires, and with the reinforcing wires stretched at the line of severance of the glass, and means for filling said recess and covering said line of severance.

6. A window pane comprising a sheet of glass reinforced by embedded wires, having a marginal strip portion thereof separated from the central portion thereof by means of cracks parallel to that edge and with the reinforcing wires unsevered and extending into the said edge portion, the crack between the severed and reinforced portions being filled with the resilient plastic material.

7. In an improved window construction, a glass pane comprising a sheet of glass reinforced by wires embedded therein and running therethrough, a marginal strip portion of the glass of the pane being severed from the body portion of the pane without severance of the reinforcing wires, the reinforcing wires at the line of severance being stretched to provide a crack of material width, the crack being filled with resilient plastic material.

8. In a window construction, a glass pane comprising a sheet of glass having reinforcement therein, a marginal strip of said pane having the glass portion thereof severed from the body of the glass along a line approximately parallel to the adjacent edge of the pane, with the reinforcement unsevered and connecting the severed glass strip to the body portion of the glass, the crack between the severed strip portion and the body of the pane being filled with a plastic resilient material.

9. In a window construction, a glass pane comprising a sheet of glass having reinforcement therein, a marginal strip of said pane having the glass portion thereof severed from the body of the glass along a line approximately parallel to the adjacent edge of the pane, with the reinforcement unsevered and connecting the severed glass strip to the body portion of the glass, the glass of said marginal strip being further severed at intervals along its length between the marginal strips at the ends of the pane, in a direction

crosswise of the length of said strip without severance of the reinforcement.

10. In a window construction, a glass pane with internal reinforcement, means covering a portion of the pane and protecting it against radiant heat, whereby a portion of said pane is subjected to radiant heat and another portion is protected from said radiant heat, the glass of said pane adjacent the junction between said protected and unprotected portions of said pane, and for the full length of such junction, being severed without severance of the reinforcement, whereby the cracking of the pane from unequal expansions due to radiant heat will be reduced.
15. 11. In a window construction, a glass pane with internal reinforcement, means covering a portion of the pane and protecting it against radiant heat, whereby a portion of said pane is subjected to radiant heat and another portion is protected from said radiant heat, the glass of said pane adjacent the junction between said protected and unprotected portions of said pane being severed without severance of the reinforcement, whereby the cracking of the pane from unequal expansions due to radiant heat will be reduced, and resilient plastic material filling the crack along the line of severance.
12. In a window construction, a sash having a recess, a glass pane having reinforcement therein disposed with a marginal edge in said recess, means filling said recess and covering the joint between said edge of the pane and said recess, the glass of said pane in a strip along and close to the outer edge of said recess and for the full length of the recess, being severed, without severance of said reinforcement, in a direction parallel to said edge, whereby the marginal edge strip received in said recess will be connected to the body of the pane by said reinforcement.

13. In a window construction, a sash having a recess, a glass pane having reinforcement therein disposed with a marginal edge in said recess, means filling said recess and covering the joint between said edge of the pane and said recess, the glass of said pane in a strip along said recess being severed, without severance of said reinforcement, in a direction parallel to said edge, whereby the marginal edge strip received in said recess will be connected to the body of the pane by said reinforcement, and the crack between said marginal strip and body of the pane being filled with a resilient plastic material.

14. An improved method of making a reinforced glass pane for window constructions and the like, where the panes will be subjected to uneven stresses due to uneven heat radiation throughout different zones, which comprises the step of severing the glass on opposite sides of the reinforcement along a marginal strip, leaving the reinforcement unsevered, and stretching the reinforcement without rupture at the line of severance to form a crack of substantial width.

15. An improved method of making a reinforced glass pane for window constructions and the like, where the panes will be subjected to uneven stresses due to uneven heat radiation throughout different zones, which comprises the step of severing the glass on opposite sides of the reinforcement along a marginal strip, leaving the reinforcement unsevered, stretching the reinforcement at the line of severance to form a crack of substantial width, and filling the crack with a resilient, adherent plastic material.
